G. C. FANNING.

WEED TURNING ATTACHMENT TO PLOWS.

APPLICATION FILED FEB. 20, 1917. RENEWED JAN. 4, 1921.

1,380,197.

Patented May 31, 1921.

UNITED STATES PATENT OFFICE.

GROVER C. FANNING, OF WICHITA, KANSAS.

WEED-TURNING ATTACHMENT TO PLOWS.

1,380,197.

Specification of Letters Patent. Patented May 31, 1921.

Application filed February 20, 1917, Serial No. 149,833. Renewed January 4, 1921. Serial No. 435,011.

To all whom it may concern:

Be it known that I, GROVER C. FANNING, a citizen of the United States, residing at Wichita, in the county of Sedgwick and 5 State of Kansas, have invented certain new and useful Improvements in Weed-Turning Attachments to Plows, of which the following is a specification.

This invention relates to a weed turning 10 attachment connected to an appropriate part of a tillage implement, and it consists in the novel combination and correlation of parts substantially as hereinafter described and particularly pointed out in the subjoined claims.

One of the important purposes of the present invention is to provide a means of simple and economical construction adapted to afford a maximum number of adjustments 20 of the weed turning member in an economical and facile way, the adjustments including the fixing of the member in its various positions to turn or bend vegetable growth in the path traversed by the member in its 25 movement with the implement to which it is applied.

Figure 1 is a perspective view of an ordinary walking plow provided with a weed turner constructed in accordance with this 30 invention;

Fig. 2 is a plan view of the members by which the weed turning member is adjustably connected to an appropriate part of a tillage implement, and shows also a part of 35 said member;

Figs. 3, 4, and 5 are detail views of the three principal members of the means for attaching the hook to the implement.

Similar characters of reference denote 40 corresponding parts in the several views.

A designates the beam of an ordinary hand plow; B the mold board of the plow bottom; and H the weed turning member. This weed turning member has an angularly disposed end h which is rigid with the body of the member, being preferably formed integral therewith, and this angularly-disposed end forms the part by which the member is wholly sustained from the 45 plow beam by a clamping means which is so constructed and so engaged with said end that the weed turning member may not only be adjusted bodily with reference to the clamping means but also may be adjusted 50 upon both vertical and horizontal axes and

may be securely fixed in any of its various positions of adjustment by the tightening of a single member.

To this end the clamp includes a fixed member E, a rotative member F and an axial member G about which the member F may be rotated when freed for such movement. The fixed member E has means (preferably those hereinafter set forth) for attaching it to an appropriate part of the beam A. The rotative member F has means (preferably the spaced bearings f' f') in which the angularly disposed end h of the weed turning member H is mounted to be adjusted longitudinally and rotatively relatively to said member F and also to partake of the rotative adjustment of said member F. The member G is formed to engage the angularly disposed end h of the weed turning member and is movable longitudinally through the axes of the members E and F of the clamp but is confined against rotative movement relatively to the rotative member F. It is arranged substantially at right angles to the end h of the weed turning member and constitutes the member which when tightened fixes the end h of the weed turning member against movement in its bearings, i. e. relatively to the member F, and also confines the rotative member F 70 against movement away from the fixed member E. The abutting faces of said members E and F are relatively so formed that the tendency of the member F to rotate in the operation of the device will be resisted 75 when the member G is tightened. It will be understood that when the member G is loosened the member F may be turned relatively to the member E and the end h of the weed turner may be moved within its 80 bearings in said member F and member G, and, as already stated, the tightening of said member G confines the member F and end h against such movements.

In the particular exemplification of the 100 invention shown in the accompanying figures of drawing, the confronting faces of the members E and F are formed with interengaging serrations or teeth, c, f, respectively, for preventing axial movement of 105 the member F when the member G is tightened, and said member F has its outer end formed with a recess, here shown as provided by spaced ears or lugs, f' having openings f² to receive the end h of the weed 110

turning member; and the member G has a flattened end G' which is fitted in the recess between the lugs or ears f' and confined thereby against axial movement relatively 5 to the member F, and said flattened end has an opening g' which registers with the openings f². Its opposite end, g, is threaded and provided with a fastening nut G². It will be apparent that the end h of the weed 10 turning member extends through the opening g' in the member G as well as through the openings f² in the member F. In practice the appliance is preferably secured to the side of the beam A, with the end h' of 15 the weed turner disposed upwardly. It is also preferred to provide the member H with a hook-end h'. The member E is rigidly connected to a plate C being in practice preferably formed integral therewith. This 20 plate C' engages the adjacent face of the beam A. A second plate D is provided to engage the opposite face of said beam. These plates are connected by bolts c, having suitable fastening nuts, not shown. By 25 this means, the entire appliance is secured to the beam A at any place in the length of the latter, i. e. adjustably longitudinally of the beam.

It will be noted that in addition to the 30 adjustment of the weed turning member H toward or away from the mold board, affected by adjusting the entire appliance along the length of the beam A, said member may be adjusted relatively to the members E, F and G of the appliance, by loosening the nut G² and then moving the end h of the member H in the openings f² and g¹ of the members F and G, and again tightening the nut G² when the required adjustment has been made. In this adjustment, the member H is raised or lowered bodily in a substantially vertical plane, when 40 the appliance is connected to the side of the beam A, as illustrated. A further adjustment, by which the hook end h' may be set at different selected positions from the ground for smaller or larger weeds is afforded when the nut G² is loosened, by turning the members F and G relatively to the member E and fixing the parts in the required new position by again tightening the nut. In this adjustment the hook moves upon an arc struck from the axis of the member G as a center. When the angularly 50 disposed end h of the member H is pivoted in the members F and G a still further adjustment of the hook end h' is provided for, as the member H may then be turned pivotally in the bearings provided by the openings f² and g¹ in the members F and G. Hence, it will be seen the member H may be readily and easily adjusted to any one of a maximum number of different positions in accord with varying requirements, by a 60 simple and economical structure and corre-

lation of parts which also effectively holds said member against accidental displacement from its selected position. It will be noted that if the member H becomes bent out of shape it may be adjusted to compensate for the distortion, thereby avoiding the necessity of reshaping it. 70

It will be understood that while I have set forth in detail the preferred embodiment and application of the invention, yet changes 75 may be made in the details and the appliance employed for other uses without departing from the spirit of the invention or the scope of the claims.

Having thus described the invention what 80 I believe to be new and desire to secure by Letters Patent, is:—

1. A weed turning appliance, comprising a weed turning member having an angularly disposed end rigid therewith, a rotative 85 clamping member having means forming a bearing within which said end may be rotated, relatively to the member; an axial member extending through the clamping member and with which said clamping 90 member and weed turning member may be rotated about an axis which is substantially at right angles to the axis of rotation of the angularly disposed end of the weed turning member, said axial member having a bearing 95 at one end for the angularly disposed end of the weed turning member and being confined against axial movement relatively to said clamping member and movable longitudinally within the latter, a fixed clamping 100 member having means for attaching it to the implement, said axial member also extending through the axis of the fixed member and said fixed and rotative clamping members having abutting faces provided with 105 elements to engage each other and hold the rotative member against rotation when so engaged, and means on the axial member to tighten and loosen it, substantially as described and for the purpose set forth. 110

2. A weed turning appliance comprising a weed turning member having an angularly disposed end rigid therewith, a rotative clamping member, a fixed clamping member, said clamping members having abutting faces provided with elements to engage each other and hold the rotative member against rotation when so engaged, means for attaching the fixed member to the beam of a plow, an axial member extending through the rotative and fixed members and movable longitudinally therein, the rotative member having spaced lugs and the axial member having a flattened end fitted in the space between said lugs to confine it against axial 115 movement relatively to the rotative member, and said lugs and flattened end having aligned openings through which the angularly disposed end of the weed turning member extends to receive rotative adjustment 120 125 130

therefrom and within which said end may be adjusted, relatively to the axial member and rotative member of the clamp, pivotally upon an axis substantially at right angle to the axis of rotation of said members of the clamp and also longitudinally, and means acting through the axial member to bind the

angularly disposed end of the weed turning member against the rotative member of the clamp and to hold the latter member against the fixed member of the clamp.

In testimony whereof I affix my signature.

GROVER C. FANNING.
